DISPLAY CABINET

Harold L. Hosley, Greensboro, N.C.

Application June 2, 1958, Serial No. 51,154

Term of patent 14 years

(Cl. D80—11)

FIG. 1

FIG. 3

FIG. 2

What I claim is:

The ornamental design for a display cabinet, as shown.
